UNITED STATES PATENT OFFICE.

SLEMMONS T. BOYD, OF SLOAN, IOWA.

FLUE-CUTTER.

No. 920,254.

Specification of Letters Patent.

Patented May 4, 1909.

Application filed December 26, 1908. Serial No. 469,398.

To all whom it may concern:

Be it known that I, SLEMMONS T. BOYD, a citizen of the United States, residing at Sloan, in the county of Woodbury and State 5 of Iowa, have invented certain new and useful Improvements in Flue-Cutters, of which the following is a specification.

My invention relates to means for cutting flues and the object is to provide a machine 10 which can be readily adjusted to the flues and will cut them quickly and thoroughly for removal from the boiler or other place where situated. I accomplish this object by the construction shown in the accompanying 15 drawing in which—

Figure 1 is a front view, Fig. 2 a plan view and Fig. 3 an inverted rear view of my invention complete. Fig. 4 is a longitudinal section on line 1—1, Fig. 1, the levers being 20 shown complete. Fig. 5 is a cross-section on line 2—2, Fig. 4, inverted, showing also the buttons for enlarging the jaws on the clamp.

In the drawing A is a round shaft the principal part of which is hollow and contains the 25 cutter levers, while the outer end is solid and threaded. B, B, are the levers pivotally secured to the shaft and its lining B', by bolts a, a, which pass through the lining and enter the shaft. The lining is in two parts, 30 the edges of each piece forming bearing surfaces for the levers and holding the levers to operation in the same plane. The projecting ends of the levers slant inwardly in their normal position to give the rolling cutters 35 C, C, a straight bearing surface. The cutters are removably secured to the levers by screw bolts b, b. Different sized cutters may be adjusted and used, according to the size of the flues. The opposite ends of the levers 40 are bowed upwardly, projecting through the slots a' in the sides of the hollow shaft A. They are normally held apart by a flat spring D secured at one end to one of the levers by a screw bolt c. The front end of 45 the shaft is supported in a rounded opening in a frame E, an internal rim e', secured to the shaft forming a bearing surface. The shaft is operated by a handle F which freely incloses the shaft and has a ratchet d adapted to engage the teeth of a rim G which is secured to the shaft close to the handle. The feed or adjustment of the cutters is regulated by a thimble H having internal threads e adapted to mesh with the threads of the shaft. The other part of the thimble 50 is hollow and fits over the shaft A, pressing

upon the levers B. As the levers are pressed into the shaft and there held by the thimble the opposite ends are opened and the cutters forced against the inside of the flue. 60

The shaft is turned by the lever F which rotates on the shaft, the thimble H being held stationary during the cutting process and the ratchet gripping the rim G and held in place by a spring f. The small end of the 65 shaft is squared internally, as seen in Figs. 3 and 4, for the reception of a rod connected with electric or other motive power, if other than hand power is employed.

I will now describe the clamp for holding 70 the cutter in place while in operation. At the end of the frame opposite the cutters are four lateral slots, g, h, i and j, in order named, from top to bottom. The upper and lower slots, g and j, are of the same size and narrow. 75 The slot h is wider than both g and j, and the slot i is wider than all the rest. In the slot h is secured a fixed upper jaw I by a cross piece k screwed to the rear end of the jaw. A movable lower jaw J is pivoted to the upper jaw by side pieces, l, l, removably secured thereto, and projects through the slot i between brackets K, K. The latter are secured to the frame by bolts and nuts m, m, through the slots g and j. The brackets each 80 have parallel vertical slots, as seen in Fig. 5, and the rear end of the lower jaw is secured between the brackets by a bolt n which passes freely through the jaw and slots and is vertically movable in the slots. Directly 85 below the lower jaw a lever L is pivotally secured between the brackets by a bolt o passing through the end of the lever and the brackets. The jaws constitute a clamp to secure the cutting machine to one of the 90 flues while the flue adjacent is being cut. The jaws are first inserted in the flue, then the lever is pressed down, which raises the rear end of the lower jaw, depressing the forward end and wedging the jaws in the 95 flue. The lower corner of the lower jaw is removed to make the insertion easier and to give a firmer bearing surface. The lateral slots are provided in order to adjust the clamp to flues at different distances from 100 each other. By loosening the bolts m securing the brackets and the screw in the piece k, the jaws may be slipped in the slots and then secured in the desired places. The jaws are each provided with threaded holes 105 in their opposite edges and may be enlarged to fit larger flues by securing the buttons M, 110

M, to the upper and lower edges by screw bolts *p*, *p*. The clamp holds the cutter firmly in its place while the work of cutting the adjacent flue progresses.

5 Having described my invention, what I claim as new and desire to secure by Letters Patent, is—

1. In a flue-cutter, the combination with a frame and an operating handle, a shaft rotatably supported in the frame and operated by the handle, cutters secured to the shaft and operated thereby, of jaws adjustably secured in the frame and adapted to be inserted in an adjacent flue, and a lever pivoted to the frame for spreading the jaws and securing a clamp in the flue, substantially as described.

2. In a flue-cutter, the combination with a frame and operating handle, a hollow shaft rotatably supported in the frame and operated by the handle, levers pivotally secured in the shaft, knives or cutters secured to said levers and means applied to the levers for regulating the feed or adjustment of the cutters, of jaws adjustably secured in the frame and adapted to be inserted in a flue, and a lever pivoted to the frame for spreading said jaws and securing the cutter during the cutting process, substantially as described.

3. In a flue-cutter, the combination with a supporting frame and means for operation of the shaft, a hollow shaft rotatably supported in the frame, levers pivotally secured to the shaft, knives secured to the levers and adapted to enter the flue, the levers being bent or

bowed outwardly near the opposite ends, a thimble to press over the ends to force the two ends of the levers together and adapted to regulate the feed or adjustment of the knives, of a clamp adjustably secured in the frame, the clamp consisting of two jaws, one of said jaws being in a fixed position and the other of said jaws being pivoted in the frame, the jaws being adapted for insertion in an adjacent flue, and a lever pivoted to the frame for spreading the movable jaw with reference to the fixed jaw, substantially as described.

4. In a flue-cutter, the combination with a frame and means for the operation of the shaft, of a hollow shaft rotatably supported in the frame, and having slots in the sides thereof, a portion of the shaft being threaded, bent levers pivotally secured in the shaft and adapted to project through the slots thereof, knives or cutters secured to said levers, and a thimble inclosing the shaft adjustable on the threads of said shaft to force the outer ends of the levers together and adapted to regulate the feed or adjustment of the knives, and means for securing the cutter to an adjacent flue during the cutting process, substantially as described.

In testimony whereof I have hereunto affixed my name in the presence of two witnesses.

SLEMMONS T. BOYD.

In the presence of—

DAVID FORSYTH,
R. Z. MITCHELL.
